United States Patent Office

Des. 185,303
Patented May 26, 1959

185,303

COMBINED CONFECTION AND HOLDER THEREFOR

Joseph Mitzenmacher, Evanston, Ill.

Application July 19, 1957, Serial No. 46,996

Term of patent 14 years

(Cl. D82—2)

Fig. 1 is a front perspective view of a combined confection and holder therefor showing my new design; Fig. 2 is a side elevational view thereof; Fig. 3 is a front elevational view; and Fig. 4 is a rear elevational view thereof.

I claim:

The ornamental design for a combined confection and holder therefor, substantially as shown.
